BRIEF CASE

Samuel H. Lifton, Brooklyn, N. Y.

Application July 31, 1935, Serial No. 34,077
Renewed September 10, 1938

4 Claims. (Cl. 150—1.6)

The subject matter of this invention is a functionally and structurally improved brief case comprising front and rear walls appropriately connected to a gusset carrying a plurality of partitions to form several longitudinally disposed article receiving compartments.

It is an object of the invention to provide a novel brief case in which marginal portions of the front and rear walls are appropriately reinforced by a strengthening resilient substantially U shaped member permitting the walls of the case to retain their normal flat shape.

It is another object of the invention to provide an improved brief case embodying spaced front and rear walls having their edges reinforced to resist wear by utilizing the marginal portions of each of the walls each to enclose and sustain a resilient member defining with respective marginal portions peripheral beads enhancing the appearance of the case.

It is another object of the invention to provide a brief case characterized by spaced front and rear walls each having a reinforced peripheral bead comprising corners appropriately strengthened by independently secured elbows.

It is a further object of the invention to provide a rugged brief case of the character described which will stand up under considerable usage and rough handling, which is practical from the standpoint of construction and which may be manufactured at a relatively low cost.

Other objects, features and advantages are in part obvious and in part pointed out hereinafter.

In the drawing which illustrates one embodiment of the present invention:

Fig. 1 is a perspective view of the brief case according to my invention.

Fig. 2 is a perspective view of the front wall of the brief case before marginal portions thereof are folded over the reinforcing member.

Fig. 3 is an elevational view of the inner face of the front wall illustrating the reinforcing member secured in position.

Fig. 4 is a longitudinal section taken on the line 4—4 of Fig. 1.

Fig. 5 is a fragmentary top view of the brief case showing the flap in a closed position.

Fig. 6 is a perspective view of an elbow utilized to reinforce the corners of the case.

Fig. 7 is a sectional view taken on the line 7—7 of Fig. 1, and

Fig. 8 is a sectional view on the line 8—8 of Fig. 1.

As illustrated, the brief case generally denoted

55 10 includes spaced front and rear walls 11 and

12 interconnected by a closed bottom bellows or gusset 13 to form a compartment 14 divided into a plurality of sub-compartments 15 by longitudinally arranged partitions 16. Walls 11 and 12 together with the intervening gusset form an article holding envelope of the well known expandible type. Walls 11 and 12 may be of a relative heavy leather or of any desired suitable material.

According to the invention, the front and rear walls are suitably reinforced and strengthened for two reasons. First, to provide a relatively rugged construction to withstand considerable use and secondly to provide a brief case adapted to retain its general flat appearance. To this end, a U shaped resilient bar or member 17 of metal having a rectangular cross section is placed along the side and lower margins 18 of the front wall 11 after which these margins are folded or stretched over contiguous parts of the bar and adhesively secured to the inner face of wall 11. In other words, the side and lower marginal portions of the front wall 11 together with the enclosed U shaped bar constitute a reinforcing peripheral bead 19 to strengthen the edges 20 of the wall 11.

Having folded the marginal portions 18 over the reinforcing bar and adhesively secured the former to the inner face of wall 11, the outer surface of the latter is appropriately creased 30 along line 20 to present the marginal outside face 21 in front of the body of the wall 11 to enhance the appearance thereof.

Rear wall 12 is similarly reinforced and strengthened but an upper portion thereof which 35 extends above the elevation of the front wall and gusset, constitutes a flap generally designated 22.

A longitudinally disposed flat and resilient strip 23 of metal is appropriately enclosed in a 40 pocket defined by the inner face of flap 22 and a longitudinally arranged flexible strip of leather 24 sewed to the flap, and appropriately attached to reinforcing strip 23 is a pair of brackets 24', each carrying yokes 25 swingably supporting 45 handle 26.

The upper marginal portion 27 of flap 22 is also reinforced by first folding the same over the U shaped reinforcing bar 28 and subsequently adhesively securing the same against the inner 50 surface of flap 22 after which the outer surface thereof is creased adjacent the outline of the reinforcing bar 28 to provide a beaded but reinforced edge 29.

Attached to flap 22 and front wall 11 is a pair 55

of complementary conveniently disconnectable locking members 30 and 31 for holding the flap in a closed position. Suitable straps as 32 are appropriately attached to the front and rear walls 5 of the case and constitute supplementary fastening means.

Portion 33 of the flap above flexible strip 24 constitutes the top wall of the case when the flap is closed. It will be noted that the part of the 10 flap just above the gusset has a length greater than the length of the front and rear walls connected to the gusset. In other words, the marginal portions 34 of the flap extend beyond the 15 sides of the gusset and overhang the latter, and accordingly tend to keep particles of liquid striking top wall 33 from entering compartment 14.

The lower marginal portions of the front and rear walls have their corner portions removed to 20 form bevels 35 defining miter joints 36 when folded over the reinforcing bar 17.

Having processed the front and rear walls in accordance with the steps hereinbefore outlined, the lower corners of the front and rear walls and the corners of the flap are each provided with a 25 reinforcing elbow generally indicated 31. Each elbow is a one piece member having a C-shaped cross section adapted to conveniently fit over a corner defined by the walls of the case. Subsequently each elbow is appropriately pressed 30 against the reinforced and embossed marginal beads, it being noted that the diverging arms 38 and 39 of each elbow includes a pair of opposing and spaced flanges 40 and 41 to each of which is integrally connected a flange or segment 42, 35 adapted to frictionally engage opposing sides of an associated wall of the case and also constitute means for further enhancing the appearance thereof.

Before applying the elbows, however, the front 40 and rear walls of the case are sewed to the front and rear walls of the gusset. For example, front wall 11 is sewed by the line of stitching 43 to the front portion of gusset 13 while the rear part of the latter is secured to the rear wall 12 by the 45 line of stitching 44, the lines of stitching being placed along or adjacent the crease lines 20 to closely pass the beaded portion of the walls about their respective reinforcing members. In the same fashion, a line of stitching 45 is applied 50 to the flap for closely surrounding the beaded portion thereof about its reinforcing member.

In the broader aspects of the invention, I do not desire to be understood as limiting its embodiments to details herein shown illustratively 55 as a wide variety of modifications may be made within the scope of the appended claims without departing from the spirit of the invention.

I claim:

1. In a brief case, the combination of, spaced front and rear flexible walls each comprising side and lower marginal portions, a reinforcing member arranged adjacent said marginal portions of each of said walls, said marginal portions of each of said walls comprising parts folded over contiguous portions of an associated member and secured to the inner face of its respective wall, said folded over portions and a respective member constituting expanded reinforced beaded means extending along sides and lower edges of associated walls, and a closed bottom gusset interconnecting said walls. 5

2. In a brief case, the combination of, flexible front and rear spaced walls each having side and lower marginal portions, a U shaped reinforcing resilient member arranged adjacent said marginal portions of each of said walls, each of said marginal portions comprising parts folded inwardly over contiguous portions of an associated member and secured to the inner face of its respective wall, said folded over portions of each wall closely encompassing an associated member and defining therewith reinforced beaded means constituting marginal edges of its respective wall, 20 and a closed bottom gusset connected to corresponding parts of said walls secured to respective inner faces thereof. 25

3. In a brief case, the combination of, spaced front and rear flexible walls each comprising side 30 and lower marginal portions, a reinforcing resilient U shaped member having a rectangular cross section arranged adjacent said marginal portion of each of said walls, said marginal portion of each of said walls comprising parts folded inwardly over contiguous parts of an associated member and secured to an inner face of its respective wall, said folded over portion and a respective member constituting reinforced beaded means extending along the side and lower edges 40 of an associated wall, and a closed bottom gusset interconnecting said walls, said rear wall having a swingable flap having marginal portions overhanging the sides of said gusset. 35

4. A collapsible hand-bag, such as a brief case, 45 comprising a front panel, a rear panel, and a gussetted bellows structure of flexible material joining said panels and thus closing expansibly three sides of the bag, the material of said panels throughout the peripheral edges of the bag being 50 folded inwardly upon themselves so as to present outwardly an unbroken and uninterrupted smooth border edge, within which the adjoining edge of the bellows structure overlies, and is secured to, the infolded panel edge, throughout the border 55 of the bag.

SAMUEL H. LIFTON.
